CLAIM

The ornamental design for a specimen holder for photometric measurement of fluids in automatic analyzers, substantially as shown.

DESCRIPTION

FIG. 1 is a top plan view of a specimen holder for photometric measurement of fluids in automatic analyzers, showing my new design;

FIG. 2 is a left side view thereof.

FIG. 3 is a bottom plan view thereof.

FIG. 4 is a right side view thereof.

FIG. 5 is a left end view thereof.

FIG. 6 is a right end view thereof.

FIG. 7 is a longitudinal sectional view taken along line 7-7' of FIG. 1.
